UNITED STATES PATENT OFFICE.

STEPHEN L. TINGLEY, OF NEW YORK, N. Y.

NITROGEN FIXATION.

No Drawing.

Application filed December 23, 1921. Serial No. 524,481.

To all whom it may concern:

Be it known that I, STEPHEN L. TINGLEY, a citizen of the United States, residing in New York, in the county of New York and 5 the State of New York, have invented certain new and useful Improvements in Nitrogen Fixation, of which the following is a specification.

The invention relates primarily to a 10 method of producing ammonia, but may be applied with equal success to various other gases capable of forming simple compounds, and which it is desired to bring into chemical combination, and the reactions may be 15 brought about in a more complete and simple manner than has heretofore been known.

With these and other objects in view the invention consists in the novel steps and combination of steps constituting the process, and in the novel method of applying the reactions, all as will be more fully hereinafter disclosed and particularly pointed out in the claims.

As an illustration of this process when 25 applied to the production of ammonia, three volumes of hydrogen and one volume of nitrogen may be bubbled, after a thorough mixing, through a liquid metal catalyst consisting of a combination of mercury and either osmium or iron, under a pressure of less than 200 atmospheres and at a temperature below the boiling point of mercury.

As but a relatively small percentage of the gases combine in each passage through 35 the catalyst, it is necessary to continuously circulate them, removing at the same time the ammonia formed and replacing it with fresh nitrogen and hydrogen. There are many methods of abstracting the ammonia, 40 but probably the simplest is by refrigeration while maintaining the pressure uniform throughout the heated and the cooled zones. The ammonia easily liquefies and may be drawn off without materially disturbing the pressure conditions. Another method consists in absorbing the ammonia in concentrated sulphuric acid, through which the 45 slightly cooled gases are passed. In this case great care is needed to avoid introducing the acid or vapors from it, into the catalyst chamber.

Although in the above illustration I employ mercury, many other metals are adapted for the work, providing always that at 55 the temperature of treatment, they are in

the liquid state, and remain in a fluid condition throughout the whole operation. The above applies to catalytic materials as a whole, but in certain cases of suspended metal powders distributed uniformly in a 60 liquid metal, this rule does not apply except in the sense that the mass is in a fluid condition. I refer particularly to cases where metal powders are possessed of strong catalytic properties, while their alloys are much 65 weaker in this respect. It is possible in many cases to incorporate them in a liquid metal without causing them to enter into a chemical combination.

Some metal powders are capable of absorbing very large volumes of certain gases, and this gaseous condensation and absorption reduces a gas to an almost nascent state. This probably explains the increased chemical activity observable in many methods of 75 applying the process. In cases such as the above in which the liquid metal mechanically carries a catalyst, as a suspended catalytic powder, the liquid metal is a true vehicle. This also applies but perhaps in a 80 more narrow sense where the liquid metal is alloyed with one or more other metals.

Iron, which is an excellent catalyst in the production of ammonia, acts very peculiarly with mercury. While it is most difficult to 85 produce what might be termed a true amalgam, it is extremely easy to obtain a fine almost colloidal suspension of iron powder in mercury. In fact the iron is in such fine state of division that it may be squeezed 90 through chamois with the mercury.

As mercury is the most common element of pronounced and undisputed metallic nature, which is liquid both at low and comparatively high temperatures, it is frequently employed as the vehicle for carrying metallic catalysts such as osmium, iridium, platinum, iron, uranium, nickel, etc., as well as the less known catalysts. The metallic combinations of mercury found to possess the greatest activity and at the same time remain in the fluid state, are the ones usually employed for this purpose. A very large number of elements unite with mercury at ordinary temperatures, and others unite by electrolysis and ordinary double decomposition to form what are termed amalgams. As examples of these may be mentioned barium, bismuth, cadmium, caesium, chromium, cobalt, gold, iron, lead, magne- 100 105 110

sium, manganese, nickel, osmium, palladium, platinum, silver, sodium, lithium, thallium, tin, zinc, thorium, arsenic, antimony, etc.

Of the many and varied advantages consequent upon the employment of a liquid catalyst, one of the most important is the decided surface-freshening induced by the movement of the gases through the mass. In this way every bubble is brought in contact with a 10 fresh metallic surface throughout its whole path.

It is well known that catalysts in the powder form, or deposited in thin layers on porous surfaces, tend rapidly to become chemically inactive owing to the formation of a thin coating or scum on the surface, or the deleterious action of poisons. This is not the case in liquids.

As liquid metal catalysts are splendid conductors and also transmit heat by convection, they are very valuable as temperature regulators. It is often advisable to maintain the temperature of the incoming gas throughout the reaction zone. This is very difficult where the reaction is strongly exothermic, and the surface of the gas and catalyst in contact become highly heated, especially as the porous base most commonly used for holding catalysts, is usually an insulating material such as asbestos, and can but slowly carry away the heat. On the other hand it is frequently desired to externally supply heat to the catalyst and raise it to a temperature considerably above that of the incoming gases. With a liquid metallic catalyst this is very simple. By a strange coincidence it has been discovered that when amalgams are used the conductivity is greater than that found with any of 40 the metals composing them.

The heat transference with a metallic vehicle is very complete no matter whether it is removing excess heat from the reaction zone or carrying heat to it. The word ve-

hicle must not be understood to refer to a 45 non-catalyst metal amalgamated or otherwise associated with the catalyst metal, as it has a broader meaning and may or may not be a catalyst itself.

On account of the great range of temperature permissible in this process, and the fact that a high temperature is always advisable and in most cases necessary to cut down the time, metals that are never classed as liquids may so act in this case. Another 50 55 advantageous feature is the lowering of the melting point brought about by alloying metals, which is most pronounced in the case of the so called fusible alloys. In one respect there are two limiting features, the 60 temperature must not be raised above the point at which ammonia decomposes into its elements nitrogen and hydrogen, otherwise the reverse action is set up.

In high pressure and temperature work 65 the containing vessels have to be constructed to withstand unusually hard conditions, and the units cannot be safely made as large as would otherwise be the case. A liquid catalyst takes up the least possible space, 70 and in addition may be withdrawn by simply opening a tap. At the same time fresh catalytic material may be introduced.

It is obvious that those skilled in the art may vary the details of the process without 75 departing from the spirit of the invention, and therefore I do not wish to be limited to the above disclosures except as may be required by the claims.

I claim:—

A method of fixing nitrogen and forming ammonia which comprises passing nitrogen and hydrogen through a liquid composition of mercury and osmium at temperatures below the boiling point of mercury and at substantial pressures but less than 200 atmospheres; substantially as described.

STEPHEN L. TINGLEY.
